UNITED STATES PATENT OFFICE

119,003

DESIGN FOR A DRESS ENSEMBLE

Joseph Lipof, Mattapan, Mass.

Application December 28, 1939, Serial No. 89,162

Term of patent 3½ years

To all whom it may concern:

Be it known that I, Joseph Lipof, a citizen of the United States and a resident of the city of Mattapan, in the county of Suffolk and State of Massachusetts, have invented a new, original, and ornamental Design for a Dress Ensemble, of which the following is a specification, reference being had to the accompanying drawing, forming a part thereof.

Fig. 1 is a front view of a dress ensemble showing my new design.

Fig. 2 is a rear view of the ensemble shown in Fig. 1.

Fig. 3 is a front view of the dress portion of the ensemble as shown in Fig. 1.

Fig. 4 is a rear view of Fig. 3.

Fig. 4 is a rear view of Fig. 3.

I claim:

The ornamental design for a dress ensemble, substantially as shown.

JOSEPH LIPOF.
